UNITED STATES PATENT OFFICE

FRANK P. MIES, OF CHICAGO, ILLINOIS

RUBBER HEEL ATTACHING MEANS

Application filed August 21, 1929. Serial No. 387,342.

The object of this invention is to provide improved means for detachably securing a rubber heel in place, the aim being to make the securing means inexpensive and simple of 5 operation and capable of use with any standard make of rubber heel.

In the accompanying drawings:

Figure 1 is a fragmental side elevation of 10 a shoe equipped with a device embodying the features of my invention.

Fig. 2 is a section on line 2—2 of Fig. 3. Fig. 3 is a section on line 3—3 of Fig. 2. Fig. 4 is a section on line 4—4 of Fig. 1.

In the drawings 1 is the backstay of the 15 shoe and 2 is the shank of the sole. 3 represents that portion of the leather heel which is retained for conjoint use with the rubber heel. The latter is indicated at 4.

The means for securing the heel 4 in place 20 comprises a sheet metal band 5 which fits around the leather heel 3. The ends of the band overlap in front of the leather heel. As shown in Fig. 2, the band 5 conforms in shape to the cross-sectional form of the leather heel. 25 That portion of the band which extends across the front side of the heel is of less height than the remainder of the band in order to accommodate the shank 2. Along the upper edge of the remainder of the band 5 30 is an inturned flange 8 adapted to engage in the crevice between the backstay 1 and the shank 2 and thus secure the band 5 against downward displacement. The lower edge of the band 5 except the end portions 6 and 7 35 has an inturned sharp edge 9 to indent the rubber heel 4 and thus hold the latter in place.

Means is provided to engage the overlapping end portions 6 and 7 and draw said end portions toward each other in order to hold 40 the main portion of the band 5 closely against the leather heel 3 and the rubber heel 4. The means herein shown for this purpose consists of a spring 10 bent to form the single coil 11 and the two arms 12. This spring is 45 made as thin as practicable so that it may

lie flat between the leather heel 3 and the rubber heel 4 without necessitating the recessing of either heel to accommodate the spring, thus permitting the heel-attaching means to be used in conjunction with any 50 standard make of rubber heel. However, if desired, the rubber heel may have a shallow recess 13 in its upper side to receive the spring.

The ends of the arms 12 are bent to form 55 hooks 14 adapted to project into openings 15 in the end portions 6 and 7 of the band. To allow for variations in the height of the leather heel these openings are preferably vertically elongated as shown in Fig. 4. In 60 order that the means for drawing the end portions 6 and 7 together shall be as inconspicuous as possible the openings 15 are in the form of narrow slits and a portion of the sheet metal adjacent to one side of each 65 slit is bent so as to overlie and conceal the hook 14.

The operation is as follows:

The leather heel which is to be provided with a rubber portion 4 is reduced in height 70 to a suitable extent. The band 5 is distended sufficiently against the tension of the spring to permit of slipping the band up over the leather heel until the flange 8 engages in the crevice between the backstay 1 and the shank 75 2. The band 5 is then sprung apart sufficiently to permit of slipping the rubber heel up into contact with the leather heel or the spring, whereupon the spring is permitted to exert tension to cause the rubber heel to 80 be tightly gripped by the lower portion of the band. It will be apparent that the operation of attaching or detaching a rubber heel is so simple that a new rubber heel may be readily substituted for one that has become worn.

The form of the securing means is such that it is inconspicuous and not readily distinguishable from a leather heel, as it will be understood that the band 5 is enameled 90

in the color corresponding to that of the shoe with which it is to be worn.

I claim as my invention:

The combination with a shoe having a heel portion, of a rubber heel, securing means for said rubber heel comprising a sheet metal band to embrace the heel portion and said rubber heel, and a spring lying between adjacent faces of the heel portion and said rubber heel causing engagement of said band with the heel portion and said rubber heel.

In testimony whereof, I have hereunto affixed my signature.

FRANK P. MIES.
